US00D910339S

(12) **United States Design Patent** (10) Patent No.: **US D910,339 S**
(45) Date of Patent: **** Feb. 16, 2021**

(54) **PILLOW**

(71) Applicant: **Denneroll Holdings Pty Ltd**, Cromer (AU)
(72) Inventor: **Adrian Dennewald**, Waverton (AU)
(73) Assignee: **DENNEROLL HOLDINGS PTY LTD**, Cromer (AU)

D276,938 S 12/1984 Pedersen

(57) **CLAIM**

The ornamental design for the pillow, as shown and described.

DESCRIPTION

FIG. 1 is a top perspective view of a pillow.

FIG. 2 is a front view of the pillow of FIG. 1.

FIG. 3 is a rear view of the pillow of FIG. 1.

FIG. 4 is a side view of the pillow of FIG. 1.

FIG. 5 is another side view of the pillow of FIG. 1.

FIG. 6 is a top view of the pillow of FIG. 1.

FIG. 7 is a bottom view of the pillow of FIG. 1; and,

FIG. 8 is a bottom perspective view of the pillow of FIG. 1.

1 Claim, 7 Drawing Sheets
